Stringer

UNITED STATES PATENT OFFICE.

AUGUST L. LUCAS, OF NEW HAVEN, CONNECTICUT.

FISHPOLE.

1,276,780.

Specification of Letters Patent. Patented Aug. 27, 1918.

Application filed January 30, 1917. Serial No. 145,386.

To all whom it may concern:

Be it known that I, AUGUST L. LUCAS, a citizen of the United States, residing at New Haven in the county of New Haven, 5 State of Connecticut, have invented certain new and useful Improvements in Fishpoles, of which the following is a specification, reference being had therein to the accompanying drawings.

- 10 My invention relates to a new and improved fish pole, having for its object, among other things, to construct a fish pole composed of telescopic sections, preferably metal, as well as to produce such a device 15 of the fewest possible parts, that may be economically constructed and readily assembled, and further, to provide means permitting the line to run internally through the length of the pole.
- 20 To these, and other ends, my invention consists in the fish pole, having certain details of construction and combinations of parts, as will be hereinafter described, and more particularly pointed out in the claims.
- 25 Referring to the drawings, in which like numerals of reference designate like parts in the several figures;

Figure 1 is a side elevation of my improved fish pole, with portions thereof 30 broken away;

Fig. 2 is an enlarged sectional view, taken upon line 2—2 of Fig. 1;

Fig. 3 is an enlarged sectional view thereof showing the several parts in their 35 relative positions when the pole is collapsed;

Fig. 4 is a side view of one of the end blocks, and

Fig. 5 is a detail view of a plug used with my invention.

40 In the practice of the invention, as herein shown, my improved fish pole consists of three sections, but a greater or less number of sections may be provided as desired.

The numeral 1 designates the handle section, having a neck portion 2 of reduced size, and the opposite end threaded at 3, with a cap 4 thereon, the same being held against accidental movement in its locked position by the spring member 5, fixed 45 thereto, having a detent 6 thereon that enters an opening in the wall of the handle member, as it registers therewith.

50 Slidably mounted within the handle section is the intermediate section 7, which is slightly tapered throughout its length, and

within the intermediate section is the end section 8, which is similarly tapered.

Within the inner ends of the intermediate and end sections is a locking device, comprising a block 9 having a longitudinal 60 groove 10 in one side thereof, which terminates at its opposite ends in the rounded throats 11, and having a recess 12 in one side thereof diametrically opposite the recess 10, the same being shorter in length 65 than said body member and within which is mounted a spring 13 having a detent 14 at its free end. The detent 14, as shown, engages an opening in the intermediate section 7, whereby the block 9 is held stationary with relation to said section and by depressing the detent to a position below said opening the block is removable for the purpose of cleaning or threading 70 the line through the pole. When the section 7 is drawn out to its full length, the detent 14 enters the opening 15 in the handle section 1 and prevents movement of the intermediate section 2 within the handle, until the detent 14 is manually depressed 75 so as to be disengaged from said recess 15, at which time said sections may be moved in relation to each other. Similar results are obtained with the detent in connection with the end section 8, the same entering 80 the opening 16 in the intermediate section. The detents and engaging devices as shown are in substantial alinement with each other; consequently when the locking blocks 9 are engaged they are, of their own accord, 85 placed in substantially an alined position; therefore the grooves therein, through which the line passes, are likewise in substantial alinement.

90 In the outer end of the end section is a block 17 with an opening 19 therethrough terminating at each end in a flaring throat 18.

When extended, the fish line passes from the reel 20 through the opening 21 in one 100 side of the handle section 1, through the recess 10 in the blocks 9, and through the opening 19 in the block 17.

105 The flaring throats in the ends of each of these blocks eliminate the sharp corners so that the fish line 26 will not be cut by frictional engagement therewith. When the pole is collapsed the fish hook is removed from the end of the line and a plug 22 attached thereto, so that the fish line may be 110

drawn up tight by the reel and the plug enter the outer end of the block 17, substantially as shown in Fig. 3.

When all of the parts are in their collapsed 5 position the end of the handle section 1 is closed by a cap 23 having a collar 24 upon the inside thereof, which engages the intermediate section 7 and prevents lateral movement thereof. This cap is held in its locked 10 position by a detent 25 connected therewith, which enters the opening 15, thereby locking said cap against accidental movement.

The cap 4 is shown as threaded onto the handle section, and the cap 23 as having a 15 sliding engagement therewith. Both of said caps may have a threaded or sliding engagement with said handle section as may be desired.

Having described my invention, what I 20 claim as new and desire to secure by Letters Patent, is:—

1. In a device of the character described, the combination with a hollow handle section, having reel retaining devices thereon, and 25 an opening through one side thereof, of a plurality of sections telescoping into said handle section, and when so assembling one end of each of said sections passes said opening and when assembled said ends are at a 30 point in the rear thereof; a locking joint block for each telescoping section for holding said section in alignment, said block having longitudinal grooves in two sides thereof; and a detent fixed at one end in one 35 of said grooves.

2. In a device of the character described, the combination with a hollow handle section, having reel retaining devices thereon, and an opening through one side thereof; of a plurality 40 of sections telescoping into said handle section; a joint block for each telescoping section; a guiding groove in one side of each of said blocks; an opening in said handle section, which opening and said grooves 45 provide means for guiding a line passing internally along the length of all of said sections.

3. In a device of the character described, the combination with a plurality of sections 50 telescoping into a handle section; a joint block carried at one end of each of said

telescoping sections for holding said sections in alignment, each block being provided with a longitudinal groove at one side thereof; a detent on each block for holding said block 55 in a fixed position relatively to the section carrying the block and said detent engaging another section at the end thereof when the latter is in an extended position.

4. In a device of the character described, the combination with a plurality of sections telescoping into a handle section; a joint block carried at one end of each of said telescoping sections for holding said sections in alignment, each block being provided with a longitudinal groove at one side thereof; a detent on each block for holding the same 60 in a fixed position relatively to the section carrying the block and said detent engaging an overlapping end of another section 65 whereby the latter section is held and locked 70 in an extended position.

5. In a collapsible rod; a base section having a butt end and a restricted tip end; another section telescoping into said base section; a joint block held in a fixed position in one end of the telescoping section by means of a detent carried by said block engaging a perforation in said section and said detent in an extended position of the telescoping 75 section engaging a perforation in the tip end of said base section which overlaps the telescoping section and whereby the latter section is held locked in an extended position. 80

6. In a telescoping fishing rod; a plurality of sections, one of which constitutes a base section, into which the other section or sections telescope; a joint block or member for each telescoping section separately secured 90 relatively thereto by means of a spring detent serving also as one of a series of means for locking said telescoping sections in an extended position and each block having a groove at one side thereof arranged in alignment with other grooves whereby internal runs are provided at intervals for a line 95 along the entire length of the telescoping sections when extended.

In testimony whereof I have hereunto af- 100 fixed my signature.

AUGUST L. LUCAS.
